ELECTRIC FUSE

John Edward Cox, Westlands, Newcastle,
EnglandApplication July 30, 1951, Serial No. 239,289
In Great Britain August 11, 1950

13 Claims. (Cl. 200—120)

1

This invention relates to electric fuses and in particular, to fuses in which one or more fusible conductors are enclosed in a tubular casing of insulating material closed at one or both ends by sealing caps. Such fuses are often known as cartridge fuses and liquid fuses, and the tubular casing may be made of material such as porcelain, glass, synthetic resin and so forth. It has been the usual practice to close the ends of the tubular bodies of such cartridge fuses by securing end caps into position by cementing them to the casing, pressing them, spinning them or providing a thin coating of metal over the end cap and body of the casing.

The objects of the present invention are to provide a form of cartridge fuse in which the ends are sealed by a simple and cheap process and are effectively rendered gas-tight, water-tight and oil-tight at the sealed joints and, if desired, to make provision for indicators of the condition of the fuse and to support the insulating core within the casing in a simple and reliable fashion, if such a core is employed.

According to the present invention, the sealed joint between the end cap and the tubular body of such an enclosed fuse is formed by one or more sealing rings of yieldable material at each end, which rings are deformed under compression when the terminal caps are forced over the body of the casing. It is most convenient to provide grooves in the outer wall of the tubular casing to house the sealing rings which are compressed when the smooth inner surface of the cap engages them, but it is possible to make a similar joint by means of grooves in the inner wall of the cap to receive yieldable rings, in which case the outer wall of the tubular casing is smooth. Such rings may be of rubber or relatively soft thermoplastic synthetic resin or other yieldable packing material.

The end caps may also be adapted to afford a support for a hollow star core of insulating material when such is employed, and then the fusible conductor is supported on the core and the casing and core filled with fine refractory powder, such as marble dust. Thus, the star core may be supported at either end by a sheet metal spigot supported by an inturned central part of the end cap and itself making a good fit within the bore of a tubular plug or bung forced into the bore of the star core at each end. Packing washers may be employed compressed between the flat end of the tubular casing and the inner flat surface of the end caps, or fitted between the inner cylindrical wall of the casing and a re-entrant central portion of the end cap. In such a case the spigot supporting the star core may also serve the purpose of a housing for an indicator of the spring compressed plunger type or the explosive capsule type. Such an indicator usually has a

2

pointed plunger rod which indicates that the fuse has been blown when the rod protrudes. In normal use the rod may be enclosed within the end cap which has a thin wall at its centre portion which may be pierced by the pin of the indicator rod and then retains the latter in its outer indicating position. Yet again the star core may have the outwardly extending sleeve-shaped terminals at each end to which the fusible conductor is connected, and this terminal may engage over and make electrical connection with an inwardly projecting spigot on the respective end cap.

In order that the invention may be clearly understood and readily carried into effect, some examples of cartridge fuses constructed in accordance with the present invention will now be more fully described with reference to the accompanying drawings, in which:

Figure 1 is a central axial section of a preferred form of the cartridge fuse;

Figure 2 is a cross-section on the line II—II;

Figure 3 is an elevation of the body of the fuse shown in Figure 1 at one end and a section of the end cap in process of being forced on to the tubular casing;

Figure 4 is an axial section of a modified form of construction;

Figure 5 is an axial section of one end of yet another form;

Figure 6 is an elevation of one form showing the end cap with a mounting bracket and terminal securing it; while

Figures 7 and 8 are respectively axial sections of two further modified forms of fuses in accordance with the invention.

Referring first to Figures 1 to 3 which show a preferred form of high tension fuse, the tubular casing 1 consists of a cylindrical tube of glass moulded with two annular grooves 2 at either end, such grooves being of semi-circular section. Each of these grooves houses a rubber ring 3 which stands up from the casing 1 before the end cap is put into position, as shown in Figure 3. At each end a sheet metal end cap 4 is pressed over the tubular casing 1 to compress and deform the rings 3, as indicated in Figure 1, and in order to avoid damage to the rings 3 or to force them out of their grooves 2, each end cap 4 has its mouth flared somewhat at 5. In this way the rings 3 are spread and form a gas and liquid-tight joint at each end of the casing 1. As shown in the drawing, each sealing ring is of sufficient volume, when compressed, to fill completely the annular groove in which it is located and there is sufficient additional material to fill a substantial part of the annular space between the cap and the casing. The spreading of the sealing material into the

annular space increases the force with which the cap grips the casing.

In this form of fuse, there is a central tubular star core 6 of porcelain moulded with a number of outwardly extending radial ribs 7, and to support this in position there is at either end an inner sheet metal cap 8 which fits resiliently over a re-entrant part 9 of the end cap 4. The inner cap 8 is also formed with a tubular spigot 10 on which the star core 6 is supported. For that purpose, at either end a yielding plug or bung 11 is forced into the bore of the star core 6, and the spigot 10 makes a good fit within the plug 11.

A helix of silver wire 12 bridging the ribs 7 is carried on the outside of the core 6 and is spot welded at its ends to the inner caps 8 which are conveniently of copper, so that this silver conductor is electrically connected between the end caps 4. The inner cap 8 at the right hand end also serves as the housing for an indicator 13 of the explosive capsule type which makes a sliding fit within the spigot 10. In the example shown, the indicator plunger 13 has a radial rod 14 pressed outwards by a light spring not shown, to engage the inner wall of the spigot 10 so as to make electrical contact between the indicator plunger 13 and the spigot 10 of the cap 8. The indicator has a forwardly pointed rod 15 enclosed within the end cap 4 which has thin wall 16 at its central part which can be pierced by the pointed rod 15 when the fuse is blown, and which then grips the rod 15 and retains it in the indicating position. The indicator 13 is exploded by a subsidiary fusible conductor consisting of a coil of tungsten wire 17. This wire at the left hand end is secured to a copper bridge piece 18 welded at its ends to the inner cap 10, and at its other end the tungsten wire 17 is connected to the inner end of the indicator 13 so as to explode the capsule in the latter when the tungsten wire 17 fuses. There is a packing ring or washer 19 of asbestos fitted between the inner wall of the casing 1 and the inner cap 8 at the left hand end.

In assembly the fuse, the right hand end cap 4 is forced on to the end of the glass tube 1 in the manner already indicated. Then the star core 6 which has previously been fitted with the end caps 8 and plugs 11, the indicator 13, the washer 21 and the silver conductor 12 and tungsten conductor 17 is pushed in from the left until the washer 21 beds against the inturned part 9 of the right hand outer cap 4. Then while the core 6 is held central, the space within the core and the outer space about the core is packed with the marble powder 20; the washer 19 is inserted and finally, the left hand end cap 4 is forced on into position.

In Figure 4, the casing 1 is similar to that shown in Figure 1, with the sealing rings 3 compressed by the end caps 4. In this case, however, at either end a packing washer 22 is compressed between the flat end and the casing and the flat inner wall of the cap 4. A further washer 23 is placed outside the cap 4 and a plain end cap 24 pressed on to the cap 4 to compress the washer 23.

In this case also, the star core 6 has ribs 7 and at either end, has a sleeve-like terminal 25 cemented on to it as shown at 42 and the silver fusible conductor 12 is spot welded to the terminals 25. The terminals 25 are arranged to fit over and make connection with the inturned spigot 26 of the end caps 4.

The assembly of the fuse is carried out much

as in Figure 1, the caps 4 and 24 being placed on the right hand end of the tube 1 first and the star core 6 previously fitted with its attachments pushed into position from the left with its right hand terminal 25 pushed over the spigot 26. The tube casing 1 and the star core 6 are then filled with powder as before and the inner cap 4 with the washer 22 and the outer cap 24 at the right hand end pushed on. The housing 27 for the indicator of the spring-pressed or explosive capsule type has its outer end 28 of enlarged diameter and its cylindrical wall slit, as shown at 29, so as to grip internally the right hand spigot 26 and to hold the housing in position. The indicator, however, is not shown in Figure 4.

In Figure 5, the construction is generally as at the right hand end of Figure 1, the end cap 4 supporting an inner cap 8 which enters a plug 11 forced into the bore of the star core 6. The spigot 10 of the inner cap 8 forms the housing for indicator 13 which is of the explosive capsule type. This plunger is formed with a number of thin collars 30 leaving grooves between them which are intended to be engaged by a pair of springy out-turned arms 39 which serve as retaining pawls when fuse is blown and the indicator 13 is forced into its outer position. The arms 39 extend inwardly from a ring held between the flat surface of the inner cap 8 and a packing ring 40. Otherwise the construction is as shown in Figure 1.

Figure 6 shows one end of a fuse according to Figures 1 or 5, wherein the spade bracket 31 also forming a terminal, is provided for mounting the fuse and is spot-brazed to the flat end of an outer end cap 4.

In Figure 7 another form of construction is shown in which the star core 6 is supported by sleeve terminals 25 extending outwardly from the star core 6 and having their outer slit ends spring over the re-entrant parts 26 of the end caps 4 and secured by circlips 41. There is also at each end a packing washer 23 between the flat end of the casing 1 and the inner flat surface of the end cap 4. The outer caps 22 are, however, omitted. This fuse is shown for stud mounting by means of a stud 32 secured in the re-entrant part 26 of the left hand end cap 4. In this fuse it is required to have a non-uniform fusible silver conductor, and as it is difficult to draw a wire of varying cross-section, the conductor is shown in Figure 7 formed of sections of relatively heavy gauge 33 with intermediate sections of finer gauge 34. These sections are connected in series, being oxy-acetylene welded together as indicated at 35.

Finally, in Figure 8, a fuse according to the invention without a star core is shown. Generally speaking, the fuse is for stud mounting as in Figure 7, and the end caps 4 are arranged similarly. There are two fusible conductors in parallel consisting of sections of heavy gauge silver wire 33 with intermediate sections 34 of finer gauge and welded at 35 as in Figure 7. These conductors, however, are merely supported by the powder filling 20 which is shaken into firm contact with the conductors. At either end, the conductors are spot welded to terminal thimbles 36 which have their outer ends split and make a push-on fit on the re-entrant parts 26 of the end caps 4. Sleeves 37 of polyvinyl chloride fit over the thimbles 36 and prevent the refractory powder 20 from entering the spaces within the thimbles 36. In this construction, the thimble terminals 36 and the sleeves 37 are located

axially by a brass locating washer 38 at either end gripped between the end of the casing 1 and the packing washer 23.

In Figures 7 and 8 the fuses are shown without indicators.

I claim:

1. An electrical fuse comprising in combination, a tubular casing of insulating material, a metallic terminal cap closing said casing at each end, said cap having a cylindrical portion telescoping a portion of said casing and providing an intervening annular space, one of said telescoping portions having an annular groove formed in its surface bounding said space, and a yieldable sealing ring compressed between the inner wall of each of said end caps and the outer wall of said casing and retained in said annular groove, and a fusible conductor enclosed in said casing and extending between said end caps, said sealing rings being engaged and deformed under compression by forcing said terminal caps over the body of said casing at both ends, each sealing ring being of sufficient volume to fill completely the annular groove in which it is mounted and to fill a substantial part of said annular space.

2. In an electrical fuse, the combination of a tubular casing of insulating material, a metallic terminal cap closing said casing at one end, said cap having a cylindrical portion telescoping a portion of said casing and providing an intervening annular space, one of said telescoping portions having an annular groove formed in its surface bounding said space, and a yieldable sealing ring compressed between the inner wall of said end cap and the outer wall of said casing and retained in said annular groove, and a fusible conductor enclosed in said casing and connected to said end cap, said sealing ring being engaged and deformed under compression by forcing said terminal cap over the end portion of said casing and being of sufficient volume to fill completely the annular groove in which it is mounted and to fill a substantial part of said annular space.

3. An electrical fuse comprising in combination, a tubular casing of insulating material, a sheet metal terminal cap tightly fitting over said casing at each end, a hollow star core of insulating material mounted within said casing and supporting a fusible conductor, a tubular plug of yieldable material forced into the bore of said star core at either end and a sheet metal hollow spigot at each end of said casing secured to the respective terminal caps and fitting within said respective tubular plug.

4. An electrical fuse as defined in claim 1, also comprising a pair of flat sealing rings each interposed between the flat surface at one end of said casing and the inner flat surface of said respective terminal cap.

5. An electrical fuse comprising in combination, a tubular casing of insulating material, a sheet metal terminal cap tightly fitting over said casing at each end, a hollow star core of insulating material mounted within said casing and supporting a fusible conductor, a tubular plug of yieldable material forced into the bore of said star core at either end, a sheet metal hollow spigot at each end of said casing secured to the respective terminal caps and fitting within said respective tubular plug and a fuse indicator with a slideable plunger and housed in said hollow spigot at one end of said casing.

6. An electrical fuse comprising in combination, a tubular casing of insulating material,

a sheet metal terminal cap tightly fitting over said casing at each end, a hollow star core of insulating material mounted within said casing and supporting a fusible conductor, a tubular plug of yieldable material forced into the bore of said star core at either end, a sheet metal hollow spigot at each end of said casing secured to the respective terminal caps and fitting within said respective tubular plug and a fuse indicator with a slideable plunger and housed in said hollow spigot at one end of said casing, said terminal cap supporting said last-mentioned spigot being formed with a thin perforable wall at its central part adapted to be pierced by the plunger of said indicator on operation of the latter and to retain said plunger in the indicating position.

7. An electrical fuse comprising in combination, a tubular casing of insulating material, a sheet metal terminal cap tightly fitting over said casing at each end and formed with an inwardly projecting tubular spigot, a hollow star core of insulating material mounted within said casing, a terminal sleeve secured to each end of said star core and projecting outwardly beyond the end of said star core to engage over and to be supported by said spigot of the respective terminal cap and to make electrical contact therewith and at least one fusible conductor supported on said star core and electrically connected at its ends to said respective terminal sleeve.

8. An electrical fuse as defined in claim 7, further comprising a sheet metal indicator housing of tubular form, said housing having an enlarged outer end rendered resilient by slits engaging the inner wall of said inwardly projecting tubular spigot at one end of said casing and making electrical contact therewith.

9. An electrical fuse as defined in claim 7, further comprising a sheet metal indicator housing of tubular form, said housing having an enlarged outer end rendered resilient by slits engaging the inner wall of said inwardly projecting tubular spigot at one end of said casing and making electrical contact therewith, and a fusible conductor housed in said star core and secured at one end to said indicator housing.

10. An electrical fuse as defined in claim 1, further comprising an additional outer end cap at each end fitted over and secured to said respective terminal cap.

11. An electrical fuse as defined in claim 7, further comprising an outer end cap at each end fitted and secured to the respective metal terminal cap.

12. An electrical fuse as defined in claim 1, wherein said fusible conductor mounted within said casing consists of a plurality of conductors of different cross-sectional areas and welded together in series.

13. An electrical fuse as defined in claim 1, and including a star core mounted between said terminal caps, and wherein said fusible conductor mounted within said casing consists of a plurality of conductors of different cross-sectional areas and welded together in series and wound on said star core.

JOHN EDWARD COX.
